[57] CLAIM

The ornamental design for an abdominal support, as shown.

DESCRIPTION

FIG. 1 is a front perspective view of an abdominal support showing our new design;

FIG. 2 is a left side elevational view thereof;

FIG. 3 is a back perspective view thereof;

FIG. 4 is a right side elevational view thereof;

FIG. 5 is a top plan view thereof; and,

FIG. 6 is a bottom plan view thereof.

The crosshatch shading shown in all views is understood to repeat throughout the indicated area.
